UNITED STATES PATENT OFFICE

WILLIAM F. GEIST, OF HUTCHINSON, KANSAS

ELECTRIC HAND LANTERN

Application filed March 9, 1929. Serial No. 345,781.

This invention relates to the class of illumination and pertains particularly to an improved type of electric hand lantern.

The primary object of this invention is to provide an improved hand lantern of the electric type which, while adapted for any use, is designed primarily for the use of trainmen.

Another object of the invention is to provide an electric lantern having an improved type of body construction which will effectively protect the lighting or illuminating unit and the battery therefor and which may at the same time be quickly and easily opened for the replacement of a battery.

Another object of the invention is to provide an improved means for controlling or switching on or off the light as desired.

A further object of the invention is to provide an electric lantern of strong and durable construction which will be relatively light in weight and designed to give the maximum of service.

The invention will be best understood from a consideration of the following detailed description taken in connection with the accompanying drawings forming a part of this specification, with the understanding, however, that the invention is not confined to any strict conformity with the showing of the drawings but may be changed or modified so long as such changes or modifications mark no material departure from the salient features of the invention as expressed in the appended claim.

In the drawings:

Figure 1 is a view in longitudinal section of the hand lantern embodying this invention;

Figure 2 is a bottom plan view of the lantern;

Figure 3 is an enlarged sectional view through one side of the wall of insulation and a portion of the battery casing;

Figure 4 is a detailed view of one end of the tubular handle showing the manner in which the same is formed for attachment to the casing.

Figure 5 is an end elevational view of a battery unit adapted for use in connection

with a lantern of the type embodying the present invention.

Referring to the drawings in detail where-in like numerals of reference indicate corresponding parts throughout the several views, the numeral 1 indicates a circular body of insulation, such for example as hard rubber, bakelite or the like which constitutes the bottom of the battery casing or chamber of the lantern.

As shown, this bottom has formed thereabout adjacent the top the inwardly inclined or bevelled shoulder 2, which connects with the annular top portion 3 which is concentric with the portion of the base lying below the shoulder and of less diameter, as shown. The central portion of this insulation base has an aperture 4 formed therethrough and secured over the top of the base is a metal contact plate 5, the central portion thereof having an aperture 6 formed therethrough which coincides with the aperture 4 of the base. Any suitable securing devices may be employed for attaching this collar or plate 5 to the base, such for example as the screws 7.

The edge of the base 1 below the shoulder 2 thereof is provided with a series of threaded bores 8, each of which is designed to receive a threaded post or stud 9 for the purpose hereinafter more fully described. While any number of these posts 9 may be attached to the base, four may be employed, as shown, with good results.

Overlying the under face of the base 1 is a reflector plate 10, the same being preferably of nickeled brass. The peripheral portion of the reflector plate 10 is turned upwardly as indicated at 11 and has its top edge bent in over the shoulder 2 of the base, as indicated at 12. Suitable openings are formed through the upturned portion 11 to permit of the extension therethrough of the bolts or studs 9.

At its central portion the reflector plate 10 is provided with the downwardly extending dome 13 which is of the same diameter as the opening 4 through the base 1 and this dome at its central portion is provided with an opening 14 surrounded by a depending threaded flange 15 which is designed to receive the base of an incandescent lamp 16.

The dome or bulged central portion 13 of the reflector plate does not extend a great distance from the plate, it being preferable that its radius be not more than one-half inch.

5 The numeral 17 indicates the battery chamber or casing for the present lantern structure which casing is, as shown, of cylindrical formation closed at one end, as indicated at 18 and adapted to have its other or open end 10 normally closed by the base 1. The lower or free edge of the casing 17 is flared, as indicated at 19 to conform to the shape of the base 1, thus providing an obliquely angled portion which overlies the outer end of the 15 casing, this terminal portion being rolled or otherwise suitably formed, as indicated at 20 to eliminate the sharp edge which would be formed by leaving the edge of the metal of the casing in its original condition.

20 The flared portion 19 of the battery casing is provided with a series of slots or recesses 21 which permit of its being engaged over the bolts or studs 9 projecting from the edge of the base and when the casing is placed in 25 position on the base with the flared portion engaging the studs or bolts in the manner described, there is then applied to each of the bolts a holding nut 22, which when drawn up securely bind the casing base and reflector 30 together.

The battery casing or chamber 17 has attached thereto a handle member which is indicated as a whole by the numeral 23, this handle being of inverted substantially U-shaped formation and preferably constructed of suitable tubular material such as copper tubing or the like. The yoke portion of the handle loops up over the upper end of the casing and the ends thereof which are split, 35 as indicated at 24 and opened out to form an attaching plate 25, are riveted or otherwise suitably secured to the wall of the battery casing adjacent the lower edge thereof.

Between each of the legs of the handle and 45 the battery casing a suitable supporting bracket 26 is positioned which makes the connection between the handle and casing firmer so that loosening of the handle cannot take place.

50 There is formed through the wall of the battery casing at a point to open into the adjacent end of one leg of the handle 23, an opening 27. Through this opening 27, which as is shown in Figure 1 is arranged in substantially the same plane or slightly above the metal plate 5, one end of a contact strip 28 extends. This contact or switch strip of metal extends upwardly in the leg of the handle and at its upper end is formed to provide a series of loops or curves 29 which frictionally engage the inner wall of the casing handle and hold the strip in position.

55 Opening through a suitable opening in the handle at the outer end of the leg through 60 which the metal switch strip 28 passes, is a

shiftable body 29 through which is formed a suitable opening or passage for the extension therethrough of the switch strip. A screw 30 is threaded into the body 29 and binds the switch strip in position and the head of this screw extends outwardly from the side of the handle providing a manipulating button by means of which the body and the attached switch strip may be shifted in the handle as desired.

70 Secured to the battery casing or chamber 17 adjacent the lower portion thereof to extend outwardly and downwardly therefrom is a plurality of supporting legs 31. The lower end of each of these legs is looped to receive a supporting base ring 32, the body of which passes through the loops 33 of the legs in the manner shown. In this manner a broad supporting base frame is provided for the lantern which will support the same a suitable 80 distance above the ground or surface upon which the lantern may be set to protect the incandescent lamp 16 from damage.

75 From the foregoing description it will be readily understood that after positioning the incandescent lamp 16 in position with its base threadedly engaged in the sleeve 15 in the central portion of the reflector plate, the battery cell 34 may be then positioned head down upon the plate 5 with the central spring 85 contact 35 thereof extending downwardly through the opening as at 4 for contact with the base of the lamp, the other contact tongue 36 of the battery engaging the plate 5 in the manner shown in Figure 1.

90 After replacement of the casing 17 on the base 1 and securing it in position by the nuts 22 contact may then be set up by manipulation of the switch button 30 to produce a flow of current through the incandescent lamp, 105 this contact being brought about by shifting the strip 28 downwardly in the handle of the lantern until the lower end extends through the aperture 27 of the casing 17 engaging the plate 5. The current from the battery then 110 flows from the plate to the contact strip, through the casing and reflector plate to the outside or shell of the incandescent lamp, then through the filament of the lamp and back to the battery through the central contact of the lamp base to the central contact 115 35 of the battery in engagement therewith. It is, of course, understood that a sufficient space must be left between the casing 17 and the edge of the plate 5 to prevent contact of these members, otherwise the current circuit 120 will remain closed resulting in continuous burning of the lamp.

Having described my invention, what I 125 claim is:

A hand lantern of the character described, comprising a bottom of insulation material having a shoulder formed thereabout adjacent the top edge thereof, a metal contact plate carried upon the upper surface of said 130

- bottom, a plate covering the under surface of the bottom and having an upturned edge portion overlying said shoulder, a battery casing open at one end and having a portion 5 of the wall offset and joined thereto by an oblique portion designed to rest upon the shoulder overlying portion of the second plate, said bottom and contact plate having a central aperture therethrough for the ex-
10 tension through the bottom of a contact of a battery in the casing, a second contact of the battery engaging said plate, means forming a part of said second plate for mounting an incandescent bulb centrally of the aperture
15 in said base, fastening elements securing the offset portion of said casing about the base, and switch means for establishing an electrical connection between the incandescent bulb holding means and said contact plate.
20 In testimony whereof I hereunto affix my signature.

WILLIAM F. GEIST.
